UNITED STATES PATENT OFFICE.

M. A. FURBUSH AND GEO. CROMPTON, OF WORCESTER, MASSACHUSETTS.

LOOMS FOR WEAVING PLAIDS, &c.

Specification of Letters Patent No. 24,206, dated May 31, 1859.

To all whom it may concern:

Be it known that we, MERRILL A. FURBUSH and GEORGE CROMPTON, both of Worcester, in the State of Massachusetts, 5 have invented certain new and useful Improvements in Looms for Weaving Plaids and other Figured Fabrics; and we do hereby declare that the following is a full, clear, and exact description thereof, reference being had to the accompanying drawings, in which—

Figure 1, is a rear elevation of the loom; Fig. 2, an elevation of the left hand side; and Fig. 3, a horizontal section taken at 15 the line A, a, of Fig. 2.

The same letters indicate like parts in all the figures.

In that class of looms for weaving plaids and other figured fabrics requiring a series 20 of shuttle boxes, and in which the shifting of the shuttle boxes is determined by a pattern chain or cylinder, it has been proposed to operate the shuttle boxes at both ends from one pattern chain or cylinder by having 25 the two sets of cams that operate the two series of shuttle boxes mounted on one shaft, and to operate these cams in either direction by having two ratchet wheels on the said shaft and in reversed directions, and 30 two pawls so that the one pattern chain or cylinder could, when so arranged, shift the shuttle boxes at both ends so as to bring the several shuttles into action in any order desired instead of being limited in the changes 35 to a regular succession, but under all circumstances the boxes at both ends were operated alike, so that with three shuttle boxes at each end only three colors could be employed although these three colors could be 40 brought into action in any order desired, and the series of shuttle boxes at each side of the loom have been operated separately by means of two pattern chains or cylinders, and duplicating the mechanism at each end, 45 but in such cases although the two series of shuttle boxes could be operated independently, the mechanism was not such as to admit of shifting the several colors in any order desired. In view of this state of the 50 art the desideratum was to produce a loom in which the series of shuttle boxes on each side could be shifted in any order desired, and in any order on either side independently of the order of shifting on the other 55 side, so that with three shuttle boxes the loom could have the capacity to work more

than three colors, and this we have accomplished by our invention the first part of which consists in the employment of two sets of ratchet wheels and appendages, each 60 set consisting of two ratchets operating in reversed directions, in combination with two sets of cams, one set of double ratchets and cams for each series of shuttle boxes, whatever may be the means employed for determining the periods of shifting the ratchets, and our said invention also consists in combining the two sets of double and reversed ratchets and the two sets of cams and two 65 series of shuttle boxes with one pattern chain 70 or cylinder so that with the one pattern chain or cylinder the shuttles at both ends may be shifted in any order desired, and in the same or in different orders on both sides.

In the accompanying drawings (a) represents the frame of a loom which may be of any suitable construction, (b) the lay with the sliding shuttle boxes (c, c) each attached to, and moved by a rod (d) connected with one end of a lever (e) receiving motion, to 75 shift the shuttle boxes, from a cam wheel (f) having a series of cam projections 1, 2, 3, all around. The lay is operated by the cranks on the shaft (g), and by a pinion (h) and cog wheel (i) imparts motion to a shaft 80 (j) below, which makes one turn to two of the lay shaft (g), and at one end the shaft (j) carries two cams (k, k) on opposite sides which act upon and vibrate a lever (l) once for each beat of the lay, and this lever 85 carries and operates two sets of ratchet hands or pawls (m, m') and (n, n') for the purpose of shifting the cam wheels (f, f') one on each side of the loom. The cam wheel (f') on the right hand side of the loom 90 is attached to, and is turned by, a shaft (o) which extends through the whole width of the loom, and the other cam wheel (f) is attached to a hub (p) that turns freely on the 95 other end of the said shaft (o).

On the hub (p) of the cam wheel (f) are secured two ratchet wheels (q, r,) having the ratchet teeth cut in opposite directions, so that one wheel will turn the cam in one direction, and the other in the opposite direction, and on the shaft (o) is to be attached another pair of reversed ratchet wheels (s, t) like the pair (q, r), and for convenience the two pairs are placed side by side, and on the same shaft, except that the pair (s, t) turn with the shaft, and the other pair (q, r) attached to the hub (p).

and turn with the cam wheel (*f*) on the shaft, so that the two cam wheels can be turned at the same time in opposite or in the same direction.

5 The cam wheels are represented as formed each of four divisions, but they may be made of a greater or a less number, and each division is sufficient to move the series of shuttle boxes to the full extent for shifting 10 three boxes on each side of the loom. When the lever (*e*) bears on the point 1 of any one division of the cam, the first shuttle box will be in line with the shuttle race of the lay, either to send out or receive a shuttle, 15 and the cam in passing from the point 1 to 2, will lift up the first shuttle box and bring the second in line with the race, and the cam in passing from the point 2 to 3 will bring the third shuttle box in line with 20 the race, and the cam being again turned in the same direction to the point 1 of the next division will let down the shuttle boxes to bring back into line the first shuttle box, but if the cam be turned from the point 3 25 in the reverse direction, the second shuttle box will be brought in line, and from the second the change may be made either to the third or to the first, and so from the first the change may be made either to the second 30 or the third, and so on through the series by simply turning the cam wheel either in the one or the other direction, and the direction in which the cam wheels are to be turned depends upon the position of the 35 ratchet hands or pawls which act upon the ratchet wheels.

Each pair of ratchet wheels has two pawls, the pair of pawls (*m m'*) for the pair of ratchets (*g r*), and the pair of pawls (*n n'*) 40 for the pair of ratchets (*s t*). The lever (*l*) which carries and actuate the pawls, is made of such thickness, in view of the close proximity of the two pairs of ratchets, that one pair of pawls is pivoted on each side. The 45 two pawls of each pair are united or formed of one piece, the one (*m*) extending up to act on the teeth of the wheel (*r*) to turn the cam in one direction, and the other (*m'*) extending under to act on the teeth of the 50 wheel (*g*) to turn the cam in the opposite direction; and so with the other pair of pawls and ratchet wheels, and the acting parts of the two pawls constituting each pair are so far apart relatively to the 55 diameter of the ratchet wheels, that when one is in action the other is relieved. The pair of pawls (*m, m'*) is suspended by a spring link (*u*) to the end of a lever (*v*), and the other pair by a like link to a like lever (*w*) 60 and these two levers rest by their weight and the suspended pawls on the rolls or

spindles (*x*) of the pattern chain or cylinder (*y*) so that as the chain or cylinder is turned and the rolls pass and lift or depress the levers (*v*) and (*w*) the pawls are respectively brought into action or relieved 65 that the cams may be turned in the required direction depending upon the pattern chain or cylinder, as that is shifted in the usual manner by the ratchet arrangement (*z*) receiving motion at each beat of the lay from the lay crank. The cams are prevented from turning too far by friction straps (*a'*) or by other suitable means.

From the foregoing it will be perceived 75 that the two series of shuttle boxes can be shifted in any desired order, and that the order of shifting on each side is entirely independent of the order of shifting on the opposite side, so that a greater variety of 80 changes can be produced than when both sides were changed in unison although in any order desired, or when both sides were changed independently of each other but both in the same order, and although we 85 have described and represented what we prefer and deem to be best, viz, both series of shuttle boxes controlled and shifted by one pattern chain or cylinder, we do not 90 wish to be understood as limiting our claim of invention to this, as by the use of one part of our invention, in connection with two pattern chains or cylinders, the same capacity of changes may be obtained. Nor do 95 we wish to be understood as limiting ourselves to the special arrangement above described, as that may be greatly varied without departing from the principle or mode of operation which distinguishes our said invention from all other things before 100 known.

What we claim as our invention and desire to secure by Letters Patent is—

1. The employment of two sets of ratchet wheels, and appendages, each set consisting 105 of reversed ratchets, substantially as described, in combination with two sets of cams and two series of shuttle boxes, substantially as, and for the purpose, specified. 2. And we also claim the two sets of 110 reversible ratchets and appendages, the two sets of cams, and two series of shuttle boxes, substantially as described, in combination with one pattern chain or cylinder, in manner substantially as, and for the purpose, 115 specified.

M. A. FURBUSH.
